UNITED STATES PATENT OFFICE.

GEORG PAUL HOPPMANN, OF BROOKLYN, NEW YORK.

BOBBED-HAIR HOLDER.

Application filed January 9, 1925. Serial No. 1,371.

In wearing a bobbed hair coiffure, the forelocks often become dishevelled and hang down over the forehead in front of the eyes. This invention has for its main object to provide a holder in which strands of hair forming the forelock are clamped to prevent said forelocks from being disarranged or moved from their original or intended position.

Another object is to provide a bobbed hair holder in which the forelock, parted and arranged on one side of the head, is locked in the holder, the latter being secured by hanging and anchoring the same on the ear of the wearer.

The above and other objects will become apparent in the description below, in which characters of reference refer to like-named parts in the drawing.

Referring briefly to the drawing, Figure 1 is an illustration showing the invention as applied to a bobbed hair coiffure.

Figure 2 is an enlarged top plan view of the left hand bobbed hair holder shown on an enlarged scale.

Figure 3 is a front elevational view of Figure 2.

Figure 4 is a cross sectional view taken on line 4—4 of Figure 3.

Referring in detail to the drawing, the numeral 10 indicates the frame of the bobbed hair holder. This frame is formed into a slender curved plate-like member and is constructed of a pair of parallel horizontal bars 12 which are integrally connected by side bars 13 and 14, the parallel horizontal bars 12 being the ones that are curved longitudinally. Figures 2, 3, and 4, illustrate the bobbed hair holder worn on the left side of the head and cooperating with the left ear of the wearer, it being borne in mind that the bobbed hair holders are used in pairs on the left and right sides of the head. The bars 12, 13, and 14, forming the rectangular frame 10, are curved on their edges to enhance the appearance of the frame. In the left hand bobbed hair holder, the side bar 13 is provided with a pair of mutually spaced-apart ears 15 between

which one end of a rod 16 is pivotally secured by a pin 17 which passes thru both of the ears 15 and rotatably anchors the bar 16 between the ears. This bar extends across the frame 10 substantially parallel thereto and projects outwardly beyond the outer edge of the side bar 14 and is formed into

a downwardly extending relatively large hook 18. The side bar 14 is provided with a lug 19 which extends outwardly from the bar and is integral therewith. This lug 60 extends outwardly at right angles to the bar and is provided with a recess 20 into which the bar 16 may be inserted thru its upper open end.

The several strands 21 which form the 65 forelock of the hair of the head, are trained to fall on the side of the head and face and terminate when the coiffure is of the bobbed hair variety at a point in front of the ears and below the top thereof. When moving 70 the head from side to side, or nodding, or thru other active movements of the head, these strands forming the forelocks become disarranged and fall in front of the face, thus giving a dishevelled appearance. To 75 guard against disarranging these forelocks, one of the holders is applied to each side of the head and firmly anchors the forelock in its desired position. In securing the holders in place, the ends of the forelocks are 80 manipulated into a compact group and the holder is opened by lifting the free end of the bar 16, which is flexible, out of the recess 20, and swinging the frame 10 outwardly. The forelock is then placed in the 85 space 22 provided between the bar 16 and the frame 10, and is locked therein by again moving the frame 10 and bar 16 together. This bar 16, after being locked in the 90 recess 20, as indicated in Figure 4, holds the 95 forelock within the space 22. In order to secure the forelock in a definite position so that it cannot fall in front of the face, the hook 18 and extension of the bar 16 are provided. This hook, after the forelock has 100 been inserted in the space 22, is slipped over the ear 23 of the wearer and is entirely concealed, as the hook 18 and the entire length of the bar 16 are under the hair and therefore cannot be seen. As the frame 10 105 is the only part to be seen, it is ornamented, giving the bars 12, 13, and 14, a curved outline intended to enhance the appearance of the coiffure, as combs do.

I claim:—

A hair holder comprising a rectangular frame formed of parallel integral bars, a pair of hinge ears on one of said bars, a recessed lug on the opposing bar, an additional flexible bar pivotally mounted between said hinge ears, said frame being 110 curved longitudinally forming a space be-

tween the flexible bar and frame, one end of said flexible bar being hinged to said ears, said frame being curved longitudinally forming a space between the flexible bar and frame, said flexible bar extending longitudinally and coursing to a position where it enters the recessed lug, the remaining

length of said additional bar being curved downwardly and inwardly to lie snugly on the side of the head in the region of the ¹⁰ ear and partly encircle the latter.

In testimony whereof I affix my signature.

GEORG PAUL HOPPMANN.
